United States Patent Office.

JOHN HENRY, OF MILLBURN, NEW JERSEY.

Design No. 4,162, dated June 21, 1870.

DESIGN FOR A FRAME FOR A PRINTING-PRESS.

The Schedule referred to in these Letters Patent and making part of the same.

To all whom it may concern:

Be it known that I, JOHN HENRY, of Millburn, in the county of Essex and State of New Jersey, have invented and produced a new and original Design for a Frame for Printing-Press; and I do hereby declare that the following is a specification thereof, reference being had to the annexed drawings making part of this specification, in which—

Figure 1 is a side elevation of the entire framework.

Figure 2 is an end view thereof.

Figure 3 is a plan view of the main frame only.

The same letters in all the figures are used to indicate like parts.

This frame is intended to be used for the reception and support of the operating mechanism of a printing-press.

In the annexed drawings—

A A represent the side pieces of the main frame, each of which may be cast in a single piece, and consists of two stout parallel horizontal beams, united together by a series of vertical columns.

The side pieces are connected by transverse beams B B, to form a rectangular frame.

C C represent two ways, parallel to each other and to the sides of the frame, and provided at intervals

with suitable bearings for the support of friction-rollers, upon which the bed-plate of the press is to move. These ways are firmly secured to the cross-beams B.

D represents a minor frame, firmly attached to the ways C and the two adjacent cross-beams B, and are intended to furnish support to the mechanism by which the bed-plate of the press is to be moved.

E E represent two horizontal beams, supported by vertical columns upon the rear end of the side pieces of the main frame, to which they are firmly bolted.

Upon them the blocks E¹ E¹, for the support of the cylinder-shaft, and the standards E² E², for the support of the feed-table, are arranged.

The parts above described may be ornamented in any manner.

I claim as my invention—

The design of a frame for a printing-press, substantially as shown and described.

In testimony whereof I have signed my name to this specification in the presence of two subscribing witnesses.

JOHN HENRY.
